UNITED STATES PATENT OFFICE.

EDGAR H. FREEMAN, OF TRENTON, NEW JERSEY, ASSIGNOR TO E. H. FREEMAN ELECTRIC COMPANY, OF TRENTON, NEW JERSEY, A CORPORATION OF NEW JERSEY.

DESIGN FOR A PORCELAIN PULL-SOCKET BODY.

53,148.

Specification for Design.

Patented Apr. 1, 1919.

Application filed October 28, 1915. Serial No. 58,500. Term of patent 14 years.

To all whom it may concern:

Be it known that I, EDGAR H. FREEMAN, a citizen of the United States, residing at Trenton, in the county of Mercer and State of New Jersey, have invented a new, original, and ornamental Design for a Porcelain Pull-Socket Body, of which the following is a specification, reference being had to the accompanying drawings, forming part thereof.

The figure is a perspective view of a porcelain pull socket body showing my new design.

I claim:

The ornamental design for a porcelain pull socket body as shown.

EDGAR H. FREEMAN.

Witnesses:

MARY E. LEE,
ANNIE A. HENRY.
